(57) **CLAIM**

The ornamental design for an adjustable roller frame, as shown and described.

DESCRIPTION

FIG. 1 is a front perspective view of an adjustable roller frame shown in a straightened operating configuration; FIG. 2 is a rear perspective view thereof; FIG. 3 is a front elevational view thereof; FIG. 4 is a rear elevational view thereof; FIG. 5 is a left side view thereof; FIG. 6 is a right side view thereof; FIG. 7 is a top view thereof; FIG. 8 is a bottom view thereof; FIG. 9 is a front perspective thereof, with the adjustable roller frame shown in an angled operating configuration; FIGS. 10-12 are side views thereof, with the adjustable roller frame being shown in various different intermediate angled operating configurations; and, FIG. 13 is a front perspective of the adjustable roller frame shown in FIG. 9 provided with a corresponding paint roller. The portions shown in broken lines form no part of the claimed design.

1 Claim, 9 Drawing Sheets
